UNITED STATES PATENT OFFICE.

EDWARD S. STIMPSON, OF HOPEDALE, MASSACHUSETTS, ASSIGNOR TO THE DRAPER COMPANY, OF SAME PLACE AND PORTLAND, MAINE.

FILLING-CHANGING MECHANISM FOR LOOMS.

SPECIFICATION forming part of Letters Patent No. 658,324, dated September 18, 1900.

Application filed June 23, 1900. Serial No. 21,264. (No model.)

To all whom it may concern:

Be it known that I, EDWARD S. STIMPSON, a citizen of the United States, and a resident of Hopedale, county of Worcester, State of Massachusetts, have invented an Improvement in Filling-Changing Mechanism for Looms, of which the following description, in connection with the accompanying drawings, is a specification, like characters on the drawings representing like parts.

In United States Patent No. 627,803, dated June 27, 1899, an automatic mechanism is shown for automatically changing the filling in a loom, the filling-carriers being mounted in a feeder which is moved intermittently by or through a strong spring to bring the filling-carriers singly into operative position for transfer, the lay operating to set the spring.

My present invention relates to filling-changing mechanism of this general type; but herein the feeder-actuating spring is set by or through the operation of the transerrer, and I have provided a novel construction and arrangement of the parts for actuating the feeder. I have also provided means for positively effecting engagement of the actuating pawl with a coöperating ratchet attached to the feeder when said pawl is retracted.

Figure 1 is a front elevation of a portion of a loom provided with filling-changing mechanism embodying my invention; and Fig. 2 is a transverse sectional view thereof on the line $\alpha\alpha$, Fig. 1, looking toward the right.

The loom-frame A, lay A³, breast-beam A⁴⁰, bunter C², the filling-changing mechanism, comprising, essentially, connected disks a a' to support the filling-carriers b , (see dotted lines, Fig. 1,) the stud a^6 , fixed on the stand a^7 , on which the disks rotate, and the ratchet wheel or teeth a^9 , attached to the hub of the disk a , and the transerrer f , may be and are substantially as shown in the patent referred to, the disks constituting a "filling-feeder," as it will be hereinafter termed.

The foot of the stand a^7 is shown as provided with a horizontal hub or bearing a^8 , through which is extended a stud f' , projecting beyond the hub at each end and held from

movement therein by suitable means, as a set-screw 2. The transerrer is mounted to rock on the stud between the disks, and a spring s , surrounding the stud, is attached at one end to the transerrer and at its other end to a cap 3, suitably pinned or otherwise secured to the stud, the spring tending to lift the transerrer into normal position, as shown in the drawings. The controlling mechanism for the transerrer, including the dog m^x , governed as to its position by the rock-shaft d' and intervening connections, may be and is substantially as shown in United States Patent No. 628,228, dated July 4, 1899. At the other end of the stud f' I have mounted the hub h of a pawl-carrier h' , having pivotally connected therewith, as at 4, Fig. 2, an upturned pawl h^x , adapted to coöperate with the ratchet a^9 , one end of the strong spring S being connected with the pawl-carrier, the other end of the spring being secured to a cap 6, fastened on the stud, the tendency of the spring being to rock the pawl-carrier in the direction of the arrow 25, Fig. 2.

The spring S is the feeder-actuating spring and it is wound or set by retraction of the pawl-carrier in the direction opposite to the arrow 25.

The hub h has secured to or forming part of it a longitudinally-extended ear h^2 , which projects over an oppositely-extended lug f^5 , secured to the hub of the transerrer, as clearly shown in Fig. 1.

When the transerrer is moved in a downward direction to transfer the filling-carrier then in operative position from the feeder to the shuttle, the lug f^5 will be lifted and it acting upon the ear h^2 depresses or retracts the pawl-carrier h' , winding or setting the feeder-actuating spring S and moving the pawl h^x into position to engage a fresh tooth on the ratchet a^9 . When the transerrer returns to its normal position, the spring S operates through the pawl-carrier and pawl to effect a partial rotation of the feeder sufficient to bring the next filling-carrier into operative position, as in the patents hereinbefore referred to.

It will be noted that the pawl-carrier is in

this invention mounted adjacent the trans-
ferrer, the fulera of the trans-
ferrer and pawl-
carrier being in alinement.

The mechanism is very simple, strong, and
5 durable, and the feeder-actuating spring is
mounted exteriorly to the feeder, where it
may be easily reached for repairs or adjustment.
In order to insure the engagement of
the pawl with the ratchet when the pawl-car-
rier is retracted, I have provided a cam to
act thereupon, said cam being herein shown
as a lug m^5 , mounted on the inner face of the
stand a^7 and adapted to engage a shoulder
 h^5 on the inner side of the pawl, the cam by
15 such engagement positively moving the pawl
toward and into operative position relative
to the ratchet. The detent-pawl d^{20} of suit-
able construction is provided to coöperate
with the ratchet and prevent retrograde move-
20 ment of the filling-feeder.

Having fully described my invention, what
I claim as new, and desire to secure by Letters
Patent, is—

1. A movable filling-feeder to hold a series
25 of filling-carriers, means to intermittently ac-
tuate the feeder, including a pawl, and a cam
to engage the pawl when retracted and posi-
tively move it into operative position.

2. A movable filling-feeder to hold a series
30 of filling-carriers, an attached ratchet, means,
including a pawl and a pawl-carrier, to inter-
mittently actuate the feeder, and a cam to
engage the pawl upon retractive movement
35 of the pawl-carrier and positively effect en-
gagement of the pawl with the ratchet.

3. A rotatable filling-feeder, an attached
ratchet, a pawl-carrier fulcrumed eccentric
to the axis of the feeder and having a pawl
to coöperate with the ratchet, to intermit-
40 tingly rotate the feeder, an actuating-spring
for the latter, set by retraction of the pawl-

carrier, a trans-
ferrer, and means controlled
by operation thereof to retract the pawl-car-
rier.

4. A rotatable filling-feeder, an attached 45
ratchet, a coöperating spring-actuated pawl,
to effect intermitting rotation of the feeder,
a trans-
ferrer, means controlled by its opera-
tion to retract the pawl, and a cam to engage
the pawl when retracted and positively effect 50
its coöperation with the ratchet.

5. A rotatable filling-feeder, an attached
ratchet, a coöperating pawl, its pawl-carrier,
a trans-
ferrer, the fulera of said pawl-carrier
and trans-
ferrer being in alinement with each 55
other, a feeder-actuating spring set by re-
traction of the pawl-carrier, and means con-
trolled by operation of the trans-
ferrer to re-
tract the pawl-carrier.

6. A rotatable filling-feeder, an attached 60
ratchet, a coöperating pawl, its pawl-carrier,
a trans-
ferrer, a fixed fulcrum-stud upon
which said trans-
ferrer and pawl-carrier are
mounted to rock, a feeder-actuating spring
set by retraction of the pawl-carrier, and con- 65
nections between the latter and the trans-
ferrer, to retract the pawl-carrier when the
trans-
ferrer is operated.

7. A rotatable filling-feeder, an attached
ratchet, a spring-actuated pawl-carrier, a 70
pawl pivotally mounted thereon to coöperate
with the ratchet, means to retract the pawl-
carrier, and a fixed cam in the path of the
pawl when retracted, to positively effect its
coöperation with the ratchet.

In testimony whereof I have signed my
name to this specification in the presence of
two subscribing witnesses.

EDWARD S. STIMPSON.
